HIGHWAY SEWER

John J. Hart, Pittsburgh, Pa.

Application April 18, 1945, Serial No. 588,908

2 Claims. (Cl. 182—3)

1

This invention relates to highway sewers and their installation, and is for a sewer which is cheaper, more sanitary and more readily installed than those heretofore in use.

Heretofore in the construction of sewers of this type, receiving basins of large capacity have been built in situ. Generally some weir and baffle arrangement provided the trap, resulting in the maintenance of a large body of stagnant water and muck at the bottom of the receiving basin. From time to time the accumulation of muck, leaves, filth and debris has to be cleaned out. In smaller cities this is usually a laborious and disagreeable manual task whereas in larger cities special equipment has been provided to aid with this work. In any case, the highway sewer is usually an unsanitary, expensive structure. It must be cleaned from time to time.

The present invention provides a sewer and method of installing the same that substantially reduces installation cost and provides a sewer which is almost if not entirely self-cleaning and which requires in most instances only the use of a high pressure hose for an occasional clean out. It eliminates the usual cess-pool-like condition at the bottom of the sewer. It therefore is useful in reducing expense of installation, expense of maintenance, and provides improved sanitation.

According to my invention, the construction is largely comprised of precast concrete slabs and a preformed trap, with the trap leading from a vertical wall of the basin. After making the necessary excavation, the contractor may quickly install the sewer with a set of slabs and a small amount of concrete.

My invention may be more fully understood by reference to the accompanying drawings, in which:

Fig. 1 is a transverse section through a sewer installation embodying my invention, showing its relation with respect to the highway and sidewalk;

Fig. 2 is a similar longitudinal section in the plane of line II—II of Fig. 1, and viewed in the direction of the arrows in Fig. 1;

Fig. 3 is a perspective view of the precast elements assembled in the relation which they occupy in the completed sewer; and

Fig. 4 is an exploded perspective view of the parts shown in Fig. 3.

In the drawings, and referring particularly to Figs. 1 and 2, S designates the street or highway, and W is the sidewalk. The top of the sewer is flush with the sidewalk and there is a drop at the edge of the sewer to the paving of the high-

2

way corresponding to the normal height of the curb.

The sewer embodying the present invention has a receiving or catch basin 2. This is formed by first digging an appropriate excavation. Four precast slabs are then set in place, providing the four vertical walls of the chamber. There are two end wall slabs which are designated 3. These are ordinarily flat slabs which may be reinforced if desired, and which are cast to desired height and thickness. There is a rear wall 4 which is also a flat slab of precast concrete and which, if need be, is also reinforced. This is an ordinary rectangular slab, except for the fact that inwardly from its vertical edges and downwardly from the top, it is provided with abutments which are on the inner face thereof, and which are designated 5. These abutments are preferably cast integrally with the slab, and are set inwardly from the vertical edges of the slab 4 a distance equal to the thickness of the end walls 3. In lieu of integral concrete abutments, the abutments may be formed by metal inserts cast on otherwise secured in place on the inner face of the rear wall slab. There is also a front wall slab 6 which is precast and which also may be reinforced. It is cast with an inverted U-shaped opening 7 at the center of the bottom. It has at each side of the top a projecting pillar portion 8. The pillars 8 are of a height predetermined by the height of the curb above the street level. Between the pillars 8, the top of the slab is at a lower level. The slab may be cast with a number of vertically projecting regularly spaced bars 9, the tops of these bars preferably being flush with the tops of the pillars 8. The bars 9 may be separate inserts or may be part of the reinforcing for this slab, and their purpose is to provide a guard or grill at the top of the sewer inlet which is provided by the recessed part of the slab between the pillars 8. On the inner face of the front slab 6 are abutments 10 which are preferably similarly formed and similarly located to the abutments 5 on the inner face of the rear slab.

Additionally, for the top of the receiving chamber there is a precast slab 11 which also may be reinforced and which is of a dimension sufficient to cover the top of the receiving chamber. It is preferably provided with a central opening 12 countersunk around the top edge to receive a manhole cover. On its under surface, set inwardly from each corner, there may be a downwardly projecting abutment 13, these abutments 13 being so positioned that they will contact the faces of the intersecting walls in the sev-

general corners. The top is level with the sidewalk.

In the making of the sewer, the necessary excavation is first dug. The excavation usually includes a trench leading from the front of the excavation toward the middle of the street where the trunk sewer is generally located. After the necessary excavation has been made, the front and rear slabs are set in place, care being taken that they are exactly plumb. Then the end walls 3 are set into place and they serve to hold the front and back panels from being pushed together. The abutments 5 and 10 on the rear and front walls respectively serve to position the tops of the end walls and prevent them from moving or being pushed inwardly. When the front and end walls have been set in place a precast or preformed large diameter terra cotta concrete, or other trap shaped conduit of a general U form is placed in the excavation leading forwardly from the catch basin to the trunk sewer. This trap is shown in Figs. 1 and 2 and is designated 14. The trap is preferably set in concrete so as to be immovable and avoid subsequent settling. In some instances the traps may be installed immediately after the excavation is made and before the walls of the catch basin are put into place. The receiving end of the trap 14, designated 14a, is received in the U-shaped opening 7 in the front wall of the receiving basin. The extreme inner end of the trap is flush with the inner face of the front wall 6. When this assembly has been completed, concrete is poured into the bottom of the chamber and is troweled or otherwise shaped so as to slope from the back and the ends toward the receiving opening of the trap. This mass of concrete designated 2a hardens and serves to fix the bottoms of the precast slabs in proper relation to each other. A calking or sealing compound may then be filled in along the corners and around the mouth of the trap. For example in Figs. 1 and 2 this sealing or calking is designated 15. Since the purpose of these sewers is to carry surface water away, it is not too important that all of the joints be absolutely tight, as leakage of some water into the ground will do no harm.

The other end of the trap 14 is of course connected through an appropriate conduit designated 16 to the trunk sewer not shown. When the installation has been otherwise complete and the concrete has been poured in around the outside of the slabs, and the sides of the excavation, the cover 11 is set into place. The abutments 13 on the inner face of the cover engage in the corners of the receiving chamber and hold the cover against shifting and also serve as further abutments to keep the tops of the vertical slabs from pressing inwardly toward each other. The sewer is set of course so that the lip 6a between the pillars 8 is flush with the street S. In the finished sewer the inlet opening to the sewer is provided at 17 and the metal bars 9 form a grill to prevent large objects from being swept into the sewer.

Highway sewers may thus be quickly and economically built. The precasting of the slabs requires merely that at each sewer location a set of the slabs along with the trap be unloaded from a truck. The truck may conveniently have a derrick for aiding in handling the slabs and in-

serting them. While the bottom might also be precast, it is preferable to cast the bottom in situ so as to accommodate for possible unevenness in the depth of the excavation and other irregularities, and more effectively seal the bottom of the receiving basin.

The trap 14 may be of a dimension to carry off water as fast as it can enter the receiving basin. However the only body of water that is present as a seal is that contained in the trap and the large mass of water and muck which is now normally present in the receiving basins of highway sewers is eliminated. If the velocity of the water is not sufficient to sweep sediment out of the trap, the sewers may be periodically cleaned in a very simple manner merely by lifting the manhole cover, inserting a hose, and projecting a high velocity stream through the trap.

An important feature of the construction of the present sewer is the opening of the receiving end of the trap into the side wall of the sewer. If the trap were formed in the bottom of the sewer, sticks and other debris might fall endwise into the trap, causing it to clog. By providing the trap opening in the side wall, sticks of a size which might otherwise cause difficulty are not likely to enter in such manner as to work into the trap.

While I have illustrated and described one specific embodiment of my invention, it will be understood that various changes and modifications may be made within the contemplation of my invention and under the scope of the following claims.

35 I claim:

1. A highway sewer comprising a wall and bottom and top portions providing a catch basin, a separate offset preformed U-shaped conduit leading through the wall at the bottom thereof to a sewer line to provide a trap, the trap being below the bottom of the basin and said bottom being shaped to drain all water therefrom to the trap, and means at the top of the wall to provide a highway sewer inlet opening.

2. A highway sewer comprising a precast front and back panel and opposite precast end panels, the panels abutting along their intersecting edges, a bottom formed in situ within the confines of the assembled panels and being shaped to drain all water to the bottom edge of one panel, said panels and bottom forming a catch basin, an offset precast U-shaped trap having one end opening through the bottom edge of the panel against which the water drains, a precast cover slab on top of the panels having a central opening covered by a manhole cover, and means at the top of a panel to provide a highway sewer inlet opening.
